PAINT BRUSH HOLDER

William G. Wolcott, Greenwich, Conn.
(25 Bramble Lane, Riverside, Conn.)

Filed June 10, 1963, Ser. No. 75,292

Term of patent 14 years

(Cl. D9—2)

Fig. 1.

Fig. 2.

Fig. 4. 3

Fig. 3.

FIG. 1 is a perspective view of a paint brush holder, showing my new design;

FIG. 2 is a plan view of one face of the holder, the opposite face being identical;

FIG. 3 is a view partially in side elevation and partially in section, taken along the line 3—3 of FIG. 2; and

FIG. 4 is a side elevation, on a reduced scale, showing the manner in which the holder is positioned in use between two containers, the broken line showing in FIG. 4 being for illustrative purposes only.

I claim:

The ornamental design for a paint brush holder, substantially as shown and described.
